SYSTEM FOR CORRECTING SOUND RECORDS

Application filed May 22, 1928. Serial No. 279,789.

This invention relates generally to sound records, and is particularly concerned with methods of perfecting the reproduction of sound. The invention, in its broadest aspect, is applicable to any type of sound record containing representations of a sound wave, and therefore may be adapted to either mechanical, photographic or other records.

Reference is here made to my copending applications filed on even date herewith, entitled "System for correcting sound records", Serial No. 279,790, and "Production of corrected sound records," Serial No. 279,791, in which are disclosed variations and extensions of the invention as herein disclosed, the broad claims generic to the common general method being included within the present application.

For the purpose of illustration, the invention is hereinafter particularly described and shown with reference to the photographic type of record. However, it will be understood that the invention is not intended to be limited thereby, but is to be considered as applicable to any record of sound vibrations. Photographic sound records may be of several types, and all such types are adaptable to the invention. One such record, the one to which I shall have particular reference in the following specification, consists of a shaded band of constant density, a variable or wavy outline representing the sound character and volume. Such records, and also the methods for their making and reproduction, are well known and need no particular description here.

In reproducing sounds from these records, a certain objectionable distortion is always introduced within the various units involved, this effect being due mainly, however, to the speaker. Recording systems may be constructed in which only a very slight distortion is introduced in making these records, and this may ordinarily be considered as negligible. The chief concern is therefore with the distortions of reproduction.

It is an object of this invention to provide a means of compensating these distortive effects so that a more perfect reproduction of the original sound will be attainable.

This invention provides a method and system for making a distortion corrected record, and it does so by introducing to the original record correction distortions that are compensatory of, or have a neutralizing effect on, the distortions which are introduced by reproduction. In the procedure herein-after described, this is done by recording the distorted reproduced sound, and utilizing this distorted record to modify the original record in such a manner that the distortive effects of the system are compensated in the modified record, and perfect reproduction is thus obtainable.

How this is done will be better understood from the following detailed description of a typical means for carrying out the invention, reference for the purpose being had to the accompanying drawings, in which:

Figure 1 shows diagrammatically a system suitable for carrying out the invention;

Fig. 2 shows an original sound record represented as a positive upon a photographic film;

Fig. 3 shows a photographic distortion record of sound as reproduced from the original sound record;

Fig. 4 shows a distortion correcting sound record;

Fig. 5 shows an original sound record corrected for distortion;

Fig. 6 is a curve representing the relation between the outlines of the original and the distortion records; and

Fig. 7 shows diagrammatically a variational system for carrying out the invention.

The invention will first be described with the assumption that no distortive effects are present in making the original sound record, or if actually present, are entirely negligible; distortion is thus exclusively introduced into the record within the reproducing system, and it will be shown how these effects are compensated. It will thereafter be pointed out that any small distortions arising in making the film, even though they may be negligible for practical purposes, will also be corrected within the system.

With reference to the drawings, Fig. 2 shows a photographic film 10 containing an 100

original positive P_o of a sound record of constant density, the variable wavy outline 11 representing the sound character. An original positive photographic record, in the terminology herein employed, is the photographic record obtained by ordinary light printing from the original negative record, not illustrated, obtained in originally recording the sound. A positive record is simply, 10 in the usual sense, the reversal of a negative, or in other words is the record which would be obtained by ordinary light printing from a negative record. These terms when applied to the type of record here referred to are of course merely relative, since either a positive or a negative may be used as the sound record, as is well known, and therefore the substitution of positives for negatives and negatives for positives throughout produces an equivalent method which falls properly within the scope of the claims using these terms. The sound record is illustrated upon the film in two sections, differing in that one is of a greater frequency than the other, but otherwise being identical and having corresponding parts indicated by like numerals. For the sake of simplicity, the record of a continuous uniform sound is chosen for representation in the drawings, but it will be understood that the various relations to be herein-after pointed out apply in the same manner to a sound wave of a complex nature. The records are shown in somewhat enlarged proportions in order to clearly indicate their various existing relations.

The positive record P_o is run through the system of Fig. 1 which consists of photographic sound reproducing and photographic sound recording systems. The reproducing system must be the same system, or one having identical characteristics, as the one which is to be finally utilized in reproducing the sound. The recording system will preferably also be the same as was used in originally making the record, or one that introduces little or no distortion. With reference to Fig. 1 the film 10 containing the positive record P_o is shown traveling between an illuminant I and a photo-electric cell P. A plate having a slit S1 is interposed between the illuminant and the photo-electric cell. Light rays from the illuminant I pass through the slit S1, are modulated by the record upon the film, and affect the photo-electric cell P. Modulated current from the photo-electric cell P is conducted into the amplifier A1, and thence reproduced as sound by the speaker unit H, this sound having the distortions of the reproducing system.

Amplifier A1, and other amplifiers to be mentioned later, may be any suitable electrical or vacuum tube amplifiers adapted to amplify an audio-frequency electrical current.

A microphone M of the sound recording

system picks up the distorted sound, a sound current being conducted therefrom through the amplifier A2 to the glow tube G, before which travels a film 20. A plate having a slit S2 is interposed between the glow-tube and the film. The film 20 thus takes a photographic distortion sound record, indicated in the figure as a negative N_d , of the distorted sound reproduced from the positive record P_o , the operation of the parts of the system being well known and requiring no further description here. It is only necessary here to note that the reproducing system I, S, P, A1, H, is the same as that which will be used in final reproduction, and that the recording system M, A2, G, S2 is the same as the one initially used for making original record P_o (or one introducing little or no distortion), so that the distortion record N_d with its sound wave line 21 is substantially a reproduction of original record P_o but with the distortions of reproduction imposed upon it. While a negative record is illustrated as being obtained upon film 20, whether this record is actually a negative or a positive, within the meaning herein employed, that is, with relation to the "positive" input record P_o , depends upon various factors such as the polarity of photo-electric cell P and microphone M with respect to their amplifiers A1 and A2. To avoid confusion, it will hereinafter be assumed in all cases throughout the specification, however, unless otherwise stated, that the systems are so arranged that no reversals from a positive record representing current to a negative record representing current, or vice-versa, are obtained, or in other words that a negative photographic record is obtained by reproduction and recordation of the sound wave representation of a positive photographic record, and vice versa. It will be understood, however, that a number of variations of the method may be carried out, for instance, by arranging the system to give a positive distortion record from a positive original record, as mentioned above, and by varying the printing operations as hereinafter indicated and described. Such variations, of course, lie within the scope of my invention.

The negative record N_d contains all of the distortions introduced within the reproducing system, those arising within the recording system being considered as relatively so small as to warrant being neglected for the present. Negative record N_d is herein-after referred to as a distortion record, and its outline as the distorted curve 21. This distorted curve 21 is shown superposed in dotted lines upon the positive record P_o in Fig. 2, and it will be seen that the distortion introduced in the reproducing system at any point in the record is represented by the difference in ordinates of the curves 11 and 21.

In this simple case, the distortion may be represented, as in Fig. 6, by a sine wave, the

ordinates of which are obtained by subtracting the ordinates of the distorted curve 21 from those of the original curve 11. Practically, the curves 11 and 21 will usually be complex, being the resultant waves of a number of simple sine waves, and in that case the differential wave representing distortion would also be a complex wave composed of a number of simple sine waves.

10 Whether the amplitude of the distorted curve 21 is greater or less than that of the original curve 11 depends generally upon the characteristics of the reproducing units, and in any specific case may depend upon 15 the varying factors of sound character. It is for this reason that the sound record has been illustrated in two sections of different frequencies, one illustrating a case in which the distortion record may be of less amplitude 20 than the original, and the other illustrating a case in which the distortion record may be of greater amplitude than the original, and it will be later seen that one and the same method serves to correct the record in either 25 case; so that in any record the distortion curve 21, compared with the original as illustrated in Fig. 2, may lie on either or both sides of the original curve 11, depending upon the varying frequency or other factors. In 30 other words, the distortion may be relatively either plus or minus with respect to the original record.

By a consideration of curves 11 and 21 of Fig. 2, it will be apparent that the action of 35 the reproducing system has been to decrease the amplitude of vibration at the frequency of the first section of the record, and to increase the amplitude of vibration at the frequency of the second. The positive record P_o 40 is now to be artificially modified by the relative addition of opacity at those points at which the distortion is relatively minus, or at which the distorted curve 21 falls below the original curve 11, and by the relative subtraction of opacity at those points at which the distortion is relatively plus, or at which the distorted curve 21 rises above the original curve 11, the amount of this modification at any point being always equal to the 45 distortion at that point. A simple manner of viewing these relations is that the modified record is made relatively as much more opaque than the original record as the distortion record is less opaque than the original record, and vice versa, as the case may be. 50 If then this modified record is run through the same reproducing system, the distortions introduced by that system will again be added and subtracted in the same sense or directions as before; but now the reproducing system causes the sound wave of the modified record to be altered within the system to the shape and proportions of the original wave, and distortionless audible reproduction of 55 the original sound wave is obtained.

How this may be done in practice will now be described. With reference to Fig. 4, the next step after obtaining distortion record N_d is to print upon the opposite edges of a film 30 a negative print N_o of the original 70 positive record P_o , and a positive record P_d of the distortion negative record N_d , the numerals 11 and 21 again representing the original and distorted curves respectively. As concern is to be merely with relative values, 75 these being represented for instance by the distance between the curves, or the difference of their ordinates, the entire areas of the original sound records P_o and N_d need not appear upon the film 30, and the films may therefore be so positioned in printing that a band 80 C of convenient width is obtained between the record outlines 11 and 21.

I then have upon film 30 a transparent correction band C in an opaque field and outlined by the curves 11 and 21. It will be apparent that if there were no distortions introduced within the system, curves 21 and 11 would be similar and the width of the band 85 would be constant. But the distorted curve 21 being of a different amplitude than the original curve 11, depending upon the amount and direction of distortion, the band varies in width by the difference of ordinates of the original and distorted curves 11 and 21 90 as they are shown in Fig. 2. These differences, which represent the distortions, are either positive or negative, as the case may be, as indicated in Fig. 6; and the width of the band C is therefore narrowed and 100 widened in accordance with these values. The width of the band C thus departs from the value which it would have if there were no distortions, by the amount of the distortions themselves. 105

A film 40, shown in Fig. 5, is then printed along one edge with an opaque correction band C' in duplication of the transparent correction band C, and with the original record P_o along the other, care being taken that 110 the two prints, the original record and the correction band, are accurately registered with each other.

I have thus added a band of opacity to the original record, this band varying in 115 width with the distortions; and the relation of these variations to the original record will now be pointed out. By a consideration of the characteristics of the opaque correction band C', and by a comparison of this band with the original and distortion record outlines 11 and 21, as shown in Fig. 2, the following may be noted. At those points of the original curve 11 at which the distorted curve 21 falls below that of the original curve. 120 125 opacity has been added to the original record P_o in a greater amount than has been added at those points at which the distorted curve rises above that of the original curve. 130 And, keeping in mind the fact that these pos-

itive and negative variations from a band of constant width (which gives rise to the variational addition of opacity just noted) are equal in amount to the magnitude of the distortions, it will be apparent that I have relatively added opacity by the amount of the distortions where the opacity of the distortion record falls below the original record, and relatively subtracted opacity by the amount of the distortions where the opacity of the distortion record rises above the original record. Another manner of stating this is that I have relatively added opacity to the original record by the amount of and negatively to the sense of the distortions.

While it is theoretically necessary only to alter the original record by the amount of and negatively to the sense of the distortions, thus applying corrections such as are indicated, with proper regard to signs, by the curve of Fig. 6, it is thought that the invention may most readily be practiced by the method outlined above; that is, by the addition to the original record of an opaque band that varies in width with the distortions as above set forth, and thus relatively both adding and subtracting opacity in accordance with the invention.

The result of running the film 40 with its altered sound record through the reproducing system will then be that the distortions inherently associated with the reproducing system will act to correct the sound waves represented by this oppositely distorted record, changing them back to the original wave shape and proportions, and thus audible sound is reproduced without distortion.

It will now be shown that any small distortions which might be introduced in making the record will also be compensated for. These effects were neglected in the previous discussion, and legitimately so, for they may be made to be of inconsequential proportions. However, the inherent nature of the system takes care of them, whatever they may be.

From a consideration of the method and system hereinbefore set out, it will be apparent that the original positive record P_o will actually contain whatever distortions are introduced by the original recording system with which it was made in the first place. And, further, the outline 21 of the distortion record N_o will actually differ from outline 11 of the original record P_o by an amount which is equal to the resultant distortion introduced by both the reproducing system and the recording system. The applied correction therefore involves the distortions of both the reproducing and recording systems, and compensates, therefore, not only for the distortions which will be introduced at any subsequent reproduction, but also compensates for the distortions introduced by the original recording system. Both the recording and reproducing systems utilized to mod-

ify the record must, of course, be the same, or have identical characteristics, as the ones used in originally recording and finally reproducing the sound.

It will now be shown how the distortion correcting record 30 or distortion correcting band C may be made without the necessity of first making the distortion negative N_d , the positive P_d being originally recorded along with a previously printed negative N_o , thus obtaining directly the correction band C. In order to carry this variation into effect, the following consideration must be taken into account. It will be noted that the sound wave current obtained by reproduction as in Fig. 2 of the positive record P_o represents a negative sound record, and with the ordinary photographic recording means, as indicated in the figure, a negative N_d is obtained. The present objective, however, is to obtain a positive P_d rather than the negative N_d and to obtain this positive directly by the operation of the system rather than by subsequent printing operations. This may be accomplished by substituting a negative N_o of the original positive P_o in the system of Fig. 1, in which case a positive P_d is obtained in place of the negative N_d ; or positive P_d may be obtained from positive P_o by a system such as illustrated in Fig. 7, in which system means are provided for recording directly the positive P_d from the negative sound record representing current obtained by reproduction of P_o . The system as there shown is similar, in part, to that of Fig. 1, and similar parts are therefore indicated by like numerals. In this case, however, the output leads 50 and 51 of amplifier A2 are in circuit with a photographic sound recording means adapted to reverse the sense of the sound wave representation before recording upon the film, this provision being made for the reason set out above. As a typical means of accomplishing this purpose, I show in circuit with the amplifier output leads 50 and 51 an electrically operated shutter actuating means 52. This means may be any which will control the position of a light intercepting shutter in accordance with an electrical sound current, and is therefore conventionally illustrated. In the form shown in the drawings, the amplifier output leads 50 and 51 are connected to a coil 53 having a movable core 54. Pivotally connected to the upper end of core 54 is a lever 55 which is fulcrumed at 56 and carries at its free end a shutter 57 adapted to traverse the light slit 58.

The traversing movement of the shutter is controlled by the sound current flowing in the coil 53, as will be understood. Light rays from a constant light source 59 are modulated by the shutter in accordance with the sound current, pass through the slit, and are recorded upon a traveling film 60 which has printed upon it a negative record N_o of the

original record P_o . The shutter is so carried and positioned with respect to the film that the record printed with No is a distortion positive record P_d , and a correction band C like that obtained in the first arrangement and illustrated in Fig. 4 is obtained. An opaque duplicate C' of this transparent band C is then printed with an original positive record P_o , as before described and illustrated in Fig. 5. Of course, a distortion positive P_d may also be obtained from an original positive P_o , as was previously described, by properly changing the polarity of the input to one of the amplifiers A_1 or A_2 , and in this case the usual glow tube light valve is used in place of the electrically actuated shutter.

The invention has thus far been described as correcting or compensating the distortions occurring in the simple recordation and reproduction of any typical sound record. The broad invention, however, has numerous applications in furtherance of this specific use. For instance, it may be embodied as applied to a correction of the distortion effects otherwise unavoidably introduced in radio broadcasting. For this purpose, sound would be broadcast from sound records in which compensation has been made for the distortions introduced in their making and reproduction, and also for the distortions introduced by the radio broadcasting set, and by the average radio receiving equipment.

While I have illustrated the invention with the aid of a constant density, varying outline sound record, it will be apparent that the essence of the invention is not limited to the relative addition and subtraction of bands of varying width, but may be considered, when applied to photographic records, as involving the addition and subtraction of opacity, and therefore any type of photographic sound record is responsive to the method. In its broadest aspect, in which is embraced all forms of sound records, it may be considered as involving the relative altering of or addition to the total opacity of the original sound record track area by the amount of, and in an opposite sense to, the distortions introduced in recording and reproduction.

It will be understood that the method and system as herein presented are to be considered as merely illustrative of and not restrictive upon the invention considered in its broadest sense, for various modifications of the method and system may be made without departing from the spirit and scope of the broader claims appended hereto. Furthermore, the method and system as herein disclosed, with its attendant equivalents, is but one of several means of reaching the same general end, by the same general principles of procedure. Other such means and systems are set out in said copending applications, all within the general broad aspects of the

invention which is both broadly and specifically claimed here.

I claim:

1. The method of making sound records that comprises, making a photographic record having a sound track area of varying total opacity of the undistorted sound, and adding to this record a band of opacity which varies from a band of constant width by the amount of and oppositely to the distortions impressed upon the sound in the operations leading to final audible reproduction of the said photographic sound record. 70

2. The method of making sound records that includes making an original photographic sound record having a sound track area of varying total opacity, making a photographic distortion sound record from and by reproduction of the original photographic sound record, and making a modified photographic record by relatively altering the original record by the amount of and in a reverse sense to the distortion as indicated by the difference in total opacity at any point between the original and distortion records, 90 all in such a manner that the distortions are relatively added reversely to the original record. 85

3. The method of making sound records that includes, making an original photographic sound record having a sound track area of varying total opacity, making a photographic distortion sound record from and by reproduction of the original, and making a modified photographic record by relatively adding to the original record at any point opacity in an amount equal to the algebraic difference obtained by subtracting the opacity of the distortion record from the opacity of the original record at that point. 100

4. The method of making sound records that includes, making an original photographic sound record having a sound track area of varying total opacity, audibly reproducing the sound, the sound thus reproduced being distorted, making a photographic distortion record of the distorted sound, making a photographic modifying record of the distortions by combining an original photographic record and the record 111 of distorted sound, and finally making a modified record by combining an original photographic record with the modifying photographic record in such a manner that opacity is relatively added to the original 120 record by the amount of and in a sense negative to the distortions of reproduction. 110

5. The method of making sound records that includes, making an original photographic positive record of a sound wave, 125 said record involving a sound track area of varying total opacity reproducing sound from this positive record, making a photographic distortion negative record of the sound as reproduced, combining upon a film 130

- a negative of the original positive record and a positive of the distortion negative record to produce a correction record representing the difference of the last two records, 5 and printing a negative of the correction record upon a film having an original positive record in such a manner that the distortions are added reversely to the original record.
10. 6. The method of making sound records that includes, making an original photographic sound record positive of the constant density, varying outline type, reproducing sound from said positive, making a distortion negative of the sound as reproduced and with the same type of record, printing side by side upon a film a negative of the original positive record and a positive of the distortion negative record, and 15 printing a negative of the record of said last mentioned film upon a film containing an original positive record in such a manner that the distortions are added reversely to the original record.
- 20 7. The method of making sound records that includes, making an original photographic positive record of the audible sound, said record involving a sound track area of varying total opacity, audibly reproducing 25 the sound, the sound thus reproduced being distorted, making a photographic distortion positive record of the distorted sound, making a photographic modifying record by combining on a film the distortion positive 30 record with a negative of the original positive record in a manner to provide a transparent corrective band which represents the reproductive distortions negatively, and combining upon a film an original positive sound 35 record and an opaque duplicate of the corrective band in register with each other in such a manner that the distortions are added reversely to the original record.
- 40 8. The method of making sound records that includes, making an original photographic positive record of the audible sound, said record involving a sound track area of varying total opacity, audibly reproducing 45 the sound, the sound thus reproduced being distorted, making a photographic distortion negative record of the distorted sound, making a photographic modifying record by combining on a film a positive of the distortion negative with a negative of the original 50 positive in a manner to provide a transparent corrective band which represents the reproductive distortions negatively, and combining upon a film an original positive sound record and an opaque duplicate of the corrective band in register with each other in such 55 a manner that the distortions are added reversely to the original record.
- 60 9. A photographic sound record consisting of, an original record having a sound track area of varying total opacity, and a 65 varying corrective band of opacity which relatively alters the total opacity of the original sound record by the amount of and in an opposite sense to the distortions introduced in reproduction of the original record. 70
10. A photographic sound record consisting of, an original record having a sound track area of varying total opacity, and a varying corrective band of opacity which relatively alters the total opacity of the original sound record by the amount of and in an opposite sense to the resultant distortions introduced in recording and reproducing the original record. 75
11. A photographic sound record consisting of, an original record having a sound track area of varying total opacity, and a varying corrective band of opacity which relatively adds opacity to the original record by the amount of and in an opposite sense to the distortions introduced in reproduction of the original record. 80
12. The method of making sound records, that includes making an original sound record, then reproducing said original sound record, obtaining from such reproduction a record of the distortions of reproduction and combining such record of distortion reversely with the original to produce a distortion compensated record. 85
13. The method of making sound records, that includes making an original photographic sound record, then reproducing said original sound record, obtaining from such reproduction a photographic record of the distortions of reproduction and combining such record of distortion reversely with the original to produce a distortion compensated record. 90
14. The method of making sound records that comprises, making a constant density varying outline photographic record of the undistorted sound, and adding to this record a band of opacity which varies from a band of constant width by the amount of and oppositely to the distortions impressed upon the sound in the operations leading to final audible reproduction of the said photographic sound record. 95
15. The method of making sound records that includes, making an original constant density varying outline photographic sound record, audibly reproducing the sound, the sound thus reproduced being distorted, making a photographic distortion record of the distorted sound, making a photographic modifying record of the distortions by combining an original photographic record and the record of distorted sound, and finally making a modified record by combining an original photographic record with the modifying photographic record in such a manner that opacity is relatively added to the original record by the amount of and in a 100
- 110
- 115
- 120
- 125
- 130

sense negative to the distortions of reproduction.

16. The method of making sound records that includes, making an original constant density varying outline photographic positive record of the audible sound, audibly reproducing the sound, the sound thus reproduced being distorted, making a photographic distortion positive record of the distorted sound, making a photographic modifying record by combining the distortion positive record with a negative of the original positive record in a manner to provide a transparent corrective band which represents the reproductive distortions negatively, and combining upon a film an original positive sound record and an opaque duplicate of the corrective band in register with each other in such a manner that the distortions are added reversely to the original record.

17. A photographic sound record consisting of a constant density varying outline original record, and a varying outline corrective band of opacity which relatively alters the original record by the amount of and in an opposite sense to the distortions introduced in reproduction of the original record.

In witness that I claim the foregoing I
have hereunto subscribed my name this 24
day of March, 1928.
